CLAIM

The ornamental design for a coffee machine, except for household purposes, as shown and described.

DESCRIPTION

Fig. 1.1 is a perspective view of my coffee machine;

Fig. 1.2 is a side perspective view thereof;

Fig. 1.3 is a front view thereof;

Fig. 1.4 is a left view thereof;

Fig. 1.5 is a right view thereof;

Fig. 1.6 is a back view thereof; and

Fig. 1.7 is a top view thereof.

In the drawings, the broken lines depict portions of the coffee machine except for household purposes that form no part of the claimed design.

1 Claim, 7 Drawing Sheets
